UNITED STATES PATENT OFFICE.

CAESER MACALE YURANOVICH, OF SEATTLE, WASHINGTON.

SUN-OBSERVING DEVICE.

Application filed May 10, 1928. Serial No. 108,181.

The invention aims to provide a new and improved device which will permit thorough examination of the sun in such manner as to determine to a greater extent than has heretofore been determined, the actual facts concerning it, and by virtue of the results obtained, will convey valuable information with regard to the influence of the sun upon all other planets, particularly the earth. The information so obtained will be of such a nature as has never before been obtained from any other source.

With the foregoing in view, the invention resides in the novel subject matter hereinabove described and claimed, the description being supplemented by the accompanying drawings.

Figure 1 is a perspective view of the complete device with the exception that part of the side wall of the booth for the observer, is broken away to show parts within the same.

Figure 2 is an enlarged vertical sectional view through the vision-tube carrier and associated parts.

Figure 3 is a bottom plan view of the parts shown in Fig. 2, partially broken away.

Figure 4 is a horizontal sectional view on line 4—4 of Fig. 2.

Figure 5 is a longitudinal sectional view through the vision tube.

In illustrating the invention, a number of details have been shown, which details have been utilized in the construction of a rather crude working device, and while I have followed these details in giving the present disclosure of the invention, it is to be understood that I am by no means restricted to them.

The numeral 6 designates a horizontal base upon which a booth 7 rests, said booth being provided with castors or the like 8, so that it may be turned upon the base to any desired position. The top 9 of the booth 7 is preferably horizontal and said top is formed with a narrow vision slot 10 which is disposed over a vision-tube 11 within the booth, said tube being preferably about ten or twelve inches above the base 6, whereas it is disposed a relatively great distance from the top 9, and these relative distances may be varied as desired and according to the number of hours per day

which the sun is to be observed. A carrier 13 is provided for the vision-tube 11 and this carrier is adjustably pivoted as at 14, to the lower ends of suitable hangers 15 which depend from the top 9 of the booth 7, wing nuts 55 or the like 16 being provided to hold the carrier 13 and the tube 11 at any desired substantially vertical or inclined position. The operator lies upon the base 6, upon a suitable pallet 17 and with one eye closed, uses the other eye to look through the vision-tube 11 and slot 10 at the sun, and by adjusting the carrier as the sun travels along its path, it may be accurately viewed for a number of hours.

Preferably, the top 9 of the booth 7 is supported by four sectional legs 18 whose sections may be detachably connected by sleeves or other suitable means 19, and the side wall of this booth is formed by a canvas curtain 70 20, said curtain having an opening 21 through which an observer may enter and leave the booth and through which his legs may project when lying upon the pallet 17. This opening is of course provided with a suitable flap 22 to exclude light and it will be understood that no light is permitted to enter the booth, except that entering through the vision slot 10.

The vision-tube carrier 13 may be of any 80 desired construction to effectively support said tube and to form a shield to protect the observer's eyes against the rays of light entering the booth through the slot 10, that is rays which would reach his eyes by a route 85 other than through the vision-tube 11, and it has been found that the rays reaching the eye through this tube, will not be objectionable or injurious to sight.

In the present showing, the carrier 13 includes a rectangular box or casing 23 which is open at its lower side and is formed with a central opening in which the upper portion of the tube 11 is secured. A dome 24 is disposed within this casing and is formed with a 95 central opening through which the tube 11 passes, the top of said dome being held in contact with the top of the casing 23, by a bottom plate 25 which is supported by appropriate cleats or the like 26—27, secured to the 100

inner sides of the casing walls, the lower edge of the dome being in contact with said bottom plate. This plate also contacts with the lower end of the vision-tube 11 and is formed 5 with a view opening 28 registering with said tube. A horizontal plate 29 spans the interior of the dome 24 and contacts with the latter near the top of said dome, said plate having an opening in which the tube 11 is secured, so that the plate tends to brace and steady the tube and prevent any angling thereof with respect to the casing 23. Another bracing plate 30 is shown extending 10 across the dome 24, between the plates 25 and 29, the central portion of said plate 30 having a clamp 31 which tightly surrounds and holds a collar 32, said collar surrounding the tube 11 near the lower end of the latter. Wedges 33 are shown inserted tightly between the 15 edge of the plate 30 and the dome 24 to neatly and securely hold said plate and dome in fixed relation, and any relative movement of the dome with respect to the casing 23, is prevented by appropriate bracing plates 34 and 20 35, secured between and in contact with said casing and dome.

The tube 11 may be composed of separate sections as illustrated in Fig. 5, said sections being designated at 36, 37, 38, 39, 40 and 41. 30 The upper section 36 is provided with a valve or shutter 42 for controlling the light passage 43 of the tube 11, said valve or shutter having an appropriate operating stem 44 provided with a knob or the like 45 by means of 35 which it may be turned. The light passage through this section 36 is preferably small, which is also true of the section 38, whereas the connecting section 37 may have a rather large internal diameter, which is also true of 40 the sections 39 and 40. The section 41 is in substantially the form of a bell shouldered at 46 to engage the collar 32, which collar is held by the clamp 31 of the plate 30. An arched cover 47 is preferably provided for the tube 45 section 36, which section projects above the top of the casing 23, said arched cover having an opening through which the stem 44 passes, leaving the knob or the like 45 accessible for adjustment of the valve or shutter 42. 50 In order that an observer lying upon the pallet 17 may rest from time to time, a shutter plate 48 is preferably slidably engaged with the plate 25, so that it may be slid across the opening 28 to cut off all light from his 55 eyes. The ends of this shutter plate may well engage the cleats 26 and may be provided with downturned guides 49 slidable in recesses 50 of said cleats. If desired, one or more cords such as at 51 may be utilized for 60 sliding the shutter plate 48 into or out of operative position.

By lying upon the pallet 17 and adjusting the carrier 13 so that with one eye, the observer may look through the slot 10 at the sun, 65 he may without any injury or discomfort,

readily study the same, thereby obtaining information of value for reasons hereinbefore set forth. Moreover, by readjusting the device from time to time, the sun may be observed for a number of hours.

In the apparatus which I have successfully used, the base 6 is about six feet square but may be circular and of about six feet in diameter if desired; the legs 18 are each approximately nine feet in length; the top 9 is 70 about three feet square and the slot 10 is three-fourths of an inch wide and about two feet eight inches long; the assemblage of parts shown in Fig. 5 has a total height of five and one-fourth inches, the diameter at the 75 lower end of the member 41 is one inch, and the openings 38—43, are each of about one-sixteenth of an inch diameter. The distance between the lower end of this assemblage and the pallet 17 is about ten or twelve inches and 80 this pallet is about two feet by five feet. 85

The details herein disclosed may be followed if desired, but within the scope of the invention as claimed, numerous variations 90 may be made.

I claim:

1. A sun observing apparatus comprising a light excluding booth having a vision slot in its top, a pallet in the booth upon which the observer lies with his face upward, a vision-tube mounted in the booth to permit the observer to look through said tube and said slot at the sun, and a shield associated with said tube to shield the observer's eyes from the sun rays entering the booth around the vision tube, through the aforesaid slot. 95
2. A structure specified as in claim 1; said tube having a varying internal diameter. 100
3. A structure specified in claim 1; said tube having a shutter for controlling the passage of light rays therethrough. 105
4. A structure specified in claim 1; said tube having a varying internal diameter and being provided with a shutter for controlling the passage of light rays therethrough. 110
5. A structure specified in claim 1; together with means whereby said vision-tube may be swung to different positions. 115
6. A structure specified in claim 1; said booth being mounted on supporting rollers for rotation about a vertical axis to any desired position. 120
7. A sun observing device comprising a base platform having a pallet upon which the observer lies face upward, a booth of light excluding nature having rollers resting on said base platform, the top of said booth having a vision slot, hangers depending from said top at opposite sides of its slot, a vision-tube carrier and face shield having combined pivotal mounting means and clamping means connecting it with the lower ends of said hangers, and a vision-tube carried by said carrier and shield, said tube and slot per- 125
8. A sun observing device comprising a base platform having a pallet upon which the observer lies face upward, a booth of light excluding nature having rollers resting on said base platform, the top of said booth having a vision slot, hangers depending from said top at opposite sides of its slot, a vision-tube carrier and face shield having combined pivotal mounting means and clamping means connecting it with the lower ends of said hangers, and a vision-tube carried by said carrier and shield, said tube and slot per- 130

1,727,686

3

mitting the observer to look therethrough at the sun.

8. In a sun observing device, a vision-tube formed of sections, the upper section having 5 a valve for controlling the passage of light rays through the tube, the lower section being in the form of an enlarged bell, intermediate sections of said tube having relatively small and large internal diameters.

10 9. In a sun observing device, a casing open at its bottom, a dome secured in said casing, a bottom plate closing the bottom of said dome and secured in the casing, said bottom plate, the top of said dome, and the top of said casing having aligned openings, a vision-tube passed through the openings of the dome and the casing top and secured thereto, the lower end of said tube resting on said bottom plate in registration with the opening thereof, and 20 a shutter for controlling the passage of light rays through said tube.

10. A structure specified in claim 9; together with a horizontal plate within said dome and having rigid engagement therewith, said plate having a central opening and being engaged thereat with said vision tube.

11. A structure specified in claim 9; together with a shutter plate slidably engaging the lower side of said bottom plate to entirely close its central opening, and means 30 slidably supporting said shutter plate.

In testimony whereof I have hereunto affixed my signature.
